Primary Examiner — Samantha Wood

(57) **CLAIM**

The ornamental design for a watch case, as shown and described.

DESCRIPTION

FIG. 1 is a top, front and right perspective view of a watch case showing my new design;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof;
FIG. 8 is an enlarged perspective view thereof taken from FIG. 1; and,
FIG. 9 is an enlarged left side view thereof taken from FIG. 4.

The broken lines in the figures illustrate portions of the watch case in FIG. 1 to FIG. 9 that form no part of the claimed design. The dome black features in FIG. 8 and FIG. 9 are shown in broken lines, and they form no part of the claimed design.

1 Claim, 9 Drawing Sheets
